UNITED STATES PATENT OFFICE.

FRANCIS LEVITT IMPEY, OF NORTHFIELD, ENGLAND.

SUPPORT FOR LOOSE-LEAF BOOKS.

1,414,281.

Specification of Letters Patent. Patented Apr. 25, 1922.

Application filed January 20, 1921. Serial No. 438,723.

To all whom it may concern:

Be it known that I, FRANCIS LEVITT IMPEY, a subject of the King of Great Britain and Ireland, residing at Kalamazoo 5 Works, Northfield, in the county of Warwick, England, have invented certain new and useful Improvements Relating to Supports for Loose-Leaf Books, of which the following is a specification.

10 This invention has for its object to construct an improved support for use with loose leaf books, especially in conjunction with mechanical account keeping.

15 The invention comprises the combination with a table or rack which may consist of two parts arranged horizontally, or at an angle, or capable of being relatively tilted, for the purpose of supporting the covers of the book, of a vertically movable abutment 20 preferably having inclined sides and capable of being raised relatively to the table for supporting the adjacent inner edges of the leaves in the two parts of an opened book.

25 The invention also comprises the combination with the abutment of means as herein-after described for engaging and securing the binding bars of the book.

Further the invention comprises mechanism as hereinafter described for actuating the aforesaid abutment and means for engaging the binding bars.

Referring to the four accompanying sheets of explanatory drawings:

35 Figure 1 is a side elevation of a loose leaf book support constructed in accordance with this invention, the movable abutment being shown in the raised position, and an opened book being indicated by dotted lines.

40 Figures 2 and 3 are respectively sectional side elevation and front elevation of the movable abutment in the raised position, Figure 4 a sectional side elevation of the abutment raised and the catches withdrawn, and Figure 5 a like view with the abutment lowered.

In carrying the invention into effect as shown, a table is constructed from two parts *a*, *b* which either occupy the same horizontal 50 plane or are relatively inclined. In conjunction with one of the parts is provided a hinged plate *c*, with a strut *d* for supporting at any desired angle the book cover resting on the said plate.

55 Between the two parts of the table and movable in a guide *e* beneath the table is

arranged an abutment *f* of inverted V-shape. The abutment is slotted transversely at suitable positions for the passage of the binding thongs or the like of the book, and it 60 is also provided with means for engaging the binding bars of the book as hereinafter described.

A vertical spindle *i* lying between the sides of the abutment has formed with it 65 a transverse cross head *j* provided with a horizontal slot. Over the spindle is arranged a relatively movable sleeve *k* attached by a cross bar *l* formed on the sleeve and screws *m*, to the inner sides of the abutment. Engaging the slot in the cross head is a crank pin *n* projecting from one side of a crank *o* which is actuated by a handle *p* arranged at one side of the table. One edge 70 of the crank is adapted to act as a cam 75 for engaging the sleeve and holding it while a relative movement is being imparted to the spindle.

To the upper end of the spindle are pivoted a pair of catches *r* for engaging the 80 binding bars *g* (Figure 1) of the book. Each catch lies in a slot in one side of the abutment, so that each of the binding bars which lie on opposite sides of the abutment is engaged by a catch. On the sleeve are 85 provided pegs *s* engaging inclined slots *t* in the catches, the arrangement being such that downward movement of the spindle relatively to the sleeve causes the catches to move 90 outwards and engage the binding bars. Upward relative movement disengages the catches.

In operation the abutment initially lies in its lower position (Figure 5). A book is then placed on one half of the support (say 95 the part *c*) and the covers are released. The uppermost cover is then turned over and placed on the part *b*, the thongs connecting the covers being caused to lie across the aforesaid slots in the abutment. Preferably 100 the parts *b* and *c* are each provided with trough like sockets *u* in which the binding bars *g* attached to the covers can be placed for securing the said bars in proper relation to the covers. In Figure 1 the parts of the 105 book are shown in diagrammatic form in dotted lines, 2 indicates the covers, and 4 the leaves. The binding thongs which pass through the slots in the abutment are omitted to avoid confusion. The two covers of 110 the book being now separated, leaving portions of the leaf binding thongs exposed,

- the abutment *j* is raised by the cross head *j* past the thongs under the action of the operating handle, and in this movement the spindle *i* and sleeve *k* move together until the 5 abutment reaches the upper limit of its motion (Figure 4). The crank pin now occupies the central position in the slot of the cross head *j*, and the sleeve is engaged by the cam edge *q* of the crank. Further movement of the handle causes the cross head *j* and consequently the catches *r* to be lowered slightly relatively to the sleeve and abutment and this movement is utilized to expand them by the action of the pegs *s* and slots *t* into 10 engagement with the binding bars, this position being shown at Figures 1, 2 and 3. During the upward movement of the abutment the transverse slots in the same permit it to pass the binding thongs of the book.
- 20 The leaves can now be manipulated as required and arranged with their edges resting against opposite sides of the abutment. Before closing the book, the leaves are all arranged on one side of the abutment, and 25 prevented from displacement by posts inserted through holes in the leaves into sockets in the lower binding bar in the ordinary manner. The abutment is then lowered to the out-of-service position, and the 30 other cover can then be placed over the leaves and secured in the usual way. In the lowering operation the first action is to disengage the catches. This is effected by the slight raising of the cross head *j* which occurs before the cam edge *q* permits the sleeve *k* to descend, the interaction of the pegs *s* and slots *t* causing the catches to be drawn together. Subsequently the catches and 35 abutment move together clear of the book to the position shown in Figure 5. In conjunction with the faces of the abutments projecting guide pieces may be arranged as heretofore for engaging notches in the adjacent edges of the leaves, but preferably 40 advantage is taken of the projecting catches for this purpose, the said catches by entering the notches in the leaves hold them against relative lateral displacement whilst at the same time securing the binding bars.
- 45 The spring *v* serves to hold the sleeve *k* on the cam edge *q* and the spring *w* to press the spindle *i* downwards, and so retain the 50 catches in effective operation.
- By this invention I am able to facilitate 55 greatly the handling of loose leaf books especially when used in conjunction with mechanical account keeping, and the transferring, replacement, or arrangement of the sheets.
- 60 The invention is not limited to any par-

ticular mechanism for actuating the abutment and catches as these and other details may be varied to meet different requirements.

Having thus described my invention what I claim as new and desire to secure by Letters Patent is:—

1. In supports for loose leaf books, the combination of two table parts, a vertically movable leaf abutment located between the said parts, and crank mechanism for raising and lowering the abutment, substantially as described.

2. In supports for loose leaf books, the combination of two table parts, a vertically movable leaf abutment between said parts, 75 outwardly extensible catches arranged in conjunction with the abutment and adapted to secure the binding bars of the book, a vertical spindle carrying the catches, a sleeve on the spindle carrying the abutment, a 80 connection between the abutment and catches whereby relative movement of said parts causes an outward or inward movement of the catches, and means for producing conjoint and independent movements of the spindle and sleeve, substantially as described.

3. In supports for loose leaf books, the combination of a pair of table parts, a vertically movable abutment between said parts, outwardly extensible catches in conjunction 90 with the abutment, a vertical spindle to which the catches are hinged, a sleeve carried on the spindle and connected to the abutment, a slotted crosshead on the spindle, a crank engaging the said crosshead, a cam in conjunction with the crank for coacting with the sleeve, the said mechanism being adapted to produce conjoint and independent movements of the spindle and sleeve, 95 pins on the sleeve engaging inclined slots 100 in the catches, and springs acting on the spindle, substantially as described.

4. In supports for loose leaf books, the combination of two table parts, a vertically movable abutment between the table parts, a 105 spindle situated in part within the abutment, a slotted crosshead on the spindle, guides beneath the table parts for the said crosshead, a sleeve mounted on the spindle and attached to the abutment, catches hinged to the upper end of the spindle, a crank engaging the crosshead, a cam in conjunction with the crank for acting on the sleeve, pins on the sleeve engaging inclined slots 110 in the catches, and springs acting on the 115 spindle, substantially as described.

In testimony whereof I have signed my name to this specification.

FRANCIS LEVITT IMPEY.
